(57) **CLAIM**

We claim the ornamental design for a nozzle for dispensing adhesives and sealants, as shown and described.

DESCRIPTION

FIG. 1 is a perspective view of the new design for a nozzle for dispensing adhesives and sealants;

FIG. 2 is a top plan view of the nozzle;

FIG. 3 is a front view of the nozzle as oriented in FIG. 2;

FIG. 4 is a side elevational view of the nozzle as oriented in FIG. 2; and,

FIG. 5 is a bottom view of the nozzle as oriented in FIG. 4.
